UNITED STATES PATENT OFFICE.

ELMER E. ASH, OF LOS ANGELES, CALIFORNIA.

FURNITURE CONSTRUCTION.

Application filed October 30, 1925. Serial No. 65,755.

Articles of furniture, such as desks and the like, which are provided with sliding drawers, are usually constructed with guide ways or runners for the drawers which ways 5 because of their construction are necessarily of considerable cross-sectional area and therefore space the drawers apart permitting dust, dirt and vermin to get in. Further, it is necessary to provide drawer division rails between the drawers at their 10 front ends to close this space and end panel rails are necessary opposite each guide way to form a firm support and place of attachment for the guides. These rails are also 15 necessary to tie the corner posts together and form a rigid framing for the support of the drawers and to carry the wood panels.

It is an object of the present invention to 20 reduce the cost of manufacture and weight of the structure by the elimination of framing members, at the same time providing a construction which is very strong and rigid, by combining wood and metal members in a manner to give such added strength and 25 to have the appearance of the usual all-wood construction. A further object is to provide metal guide-ways for the drawers so constructed as to take up but little space and thus permit each drawer to form a closure 30 for the drawer below, said guide-ways also being of a form to give strength and rigidity to the framing sufficient to permit of the dispensing with the use of parts of the framing, thus reducing the weight and cost of 35 manufacture of the structure.

With the above and other ends in view, the invention consists in the matters herein- 40 after set forth and more particularly pointed out in the appended claim, reference being had to the accompanying drawings in which

Figure 1 is a vertical section upon the line 1—1 of Fig. 2 of a desk illustrative of an embodiment of the invention;

Fig. 2 is a front elevation of an end portion of the desk shown in Fig. 1;

Fig. 3 is a perspective detail illustrative of the construction and showing portions of a corner post, panel rails, end panels, metal drawer guides, and wood top, and the manner in which the same are assembled; and

Fig. 4 is a perspective view of a combined wood and metal drawer.

For the purpose of illustration, the invention is shown as embodied in a desk 55 construction but it is to be understood that

the same may be embodied as well in other articles of furniture embodying drawers.

In the drawing, 1 indicates corner posts of a frame work, 2 end panel bottom rails, 3 a front division rail, and 4 a rear connecting rail, said rails being mortised into said posts to rigidly connect the same below the horizontal plane of the bottom of the lower of the several drawers 5 supported in this frame. The upper ends of the posts are 65 rigidly connected by a table top 6 secured thereto in any suitable manner not shown, or by any other suitable means to form a rectangular frame for the support of the several drawers 5 which drawers may be constructed in any suitable manner, but preferably with a front end 5^a of wood, which drawer ends, when the several drawers are in place and closed, together form a front closure for the space between the front corner posts 1 70 and the top 2 and the front rail 3 of the pedestal or drawer compartment of the desk.

The several drawers are supported and guided upon bearers or guides 7 each preferably formed from sheet metal, the sheet of metal being bent longitudinally along central parallel lines with the central portion of the sheet folded upon itself to form a longitudinal laterally projecting rib 8 with flanges 9 extending upwardly and downwardly from the base of said rib, the member thus formed being of T-formation in cross section. Two of these guide members are provided for each drawer, the members of each pair being secured at their ends by 80 means of screws 10 or other suitable means, to the inner face of the front corner posts at one end and to the rear corner posts at their rear ends with the flanges of each member extending vertically and let into the 85 inner faces of the posts to lie flush therewith and with the rib 8 extending inwardly in a horizontal position, forming a ledge to engage beneath the bottom of the drawer supported thereby with the upper flange 90 of the guide engaging the outer surface of the drawer side wall and guiding the drawer in its movement. The downwardly extending flange of each member is adapted to engage the outer surface of the side wall 100 of a drawer below, the upper edge of said side wall of the lower drawer sliding freely just beneath the rib. The superposed drawers are therefore spaced apart the thickness 105 of the rib only, so that when the drawers

are closed, each forms a cover or closure for the one next below and dust, dirt and rodents are prevented from getting in and space in height is saved over that required where the ordinary form of guide is used. Because of this close spacing of the drawers, the usual front division rails between the front ends 5^a of the drawers may be dispensed with and said ends formed to meet and completely close this small space between them, thus saving material and labor in constructing the framing.

These guide members 7, because of their T-form are very strong and rigid, and therefore provide a rigid connection between the front and rear corner posts, so that the usual end panel rails to which the drawer guides are usually secured, may be dispensed with, further cheapening the construction and decreasing its weight, these guide members being very light in weight due to their formation from sheet metal, and further, the form of each guide is such that its rib not only forms a support upon which the drawer slides, but also a members to engage the upper edge of the drawer below, to prevent the drawers from tilting downwardly when drawn out, and the flanges 9 guide the drawers laterally, so that the drawers are accurately guided and prevented from binding in their ways, thus insuring free sliding movement.

In the drawing, bottom end panel rails 2 are shown, but such rails may be dispensed with if found desirable or made a part of the end panels 11, as the front and rear corner posts are rigidly tied together by the guide members 7, and where the desk is provided with a slide 12, as shown, the guide members which are provided to engage the upper edges of the side walls of the upper drawer, may also form guides for this slide, and these members then serve to tie the front and rear corner posts together adjacent the table top 6, lending further rigidity to the structure without materially lessening the available drawer space within the frame. The guide members for the lower drawer of the series, are secured at their ends not only to the front and rear posts, but also to the front division rail 3 and rear connecting

rail 4 by securing the ends of the ribs 8 of these members to these rails by the screws 10. These guide members thus serve as corner irons to strengthen and brace the meeting angle of said rails and posts.

By employing these sheet metal drawer guides which also serve as frame members and employing wood corner posts and wood panels which completely conceal these metal guides, an article of furniture may be constructed which has the appearance of the usual wood construction but is lighter in weight and cheaper to construct, is very strong and rigid, and in which the drawers are accurately guided to slide freely, these metal guides not being subject to material expansion or contraction due to weather conditions which would cause the drawers to stick or bind therein.

Having thus fully described my invention, what I claim is:

In an article of furniture formed of metal and wood and having a supporting frame formed of wood including wooden posts and wooden front cross rail, a series of superposed drawers between said posts, each drawer having a sheet metal body and a front end formed of wood with the wooden end overlapping the end edges of the body, guides for said drawers comprising members formed of sheet metal and each provided with an outstanding rib which is thin in cross section to project between adjacent superposed drawers with the upper drawer resting upon said rib and the upper edge of the drawer below engaging the underside of said rib, said drawers being spaced apart the thickness of said rib only, and each guide formed with a flange extending upwardly from said rib and a flange extending downwardly therefrom, said flanges being secured at their ends to the inner sides of said posts, certain of said guides being secured within the meeting angle between said posts and front rail of said wooden frame with a flange of each guide secured to a post and an end portion of said rib secured to said rail, whereby said metal guides form a bracing for said wood frame.

In testimony whereof I affix my signature.
ELMER E. ASH.
